UNITED STATES PATENT OFFICE

HOMER W. JONES, OF WILLIAMSVILLE, NEW YORK, ASSIGNOR TO NATIONAL CARBON COMPANY, INC., A CORPORATION OF NEW YORK

BATTERY HAND LAMP

Application filed December 6, 1929. Serial No. 412,169.

My invention relates to battery hand lamps, flashlights and the like, and, more particularly, to an improved lamp head for maintaining a beam of light in any direction it may be positioned.

Battery hand lamps are used in many places where it is desirable to place the lamp at rest in order to obtain the free use of both hands while the light is directed upon some desired object. In using hand lamps heretofore constructed delay or inconvenience is encountered in finding some means such as a prop or hook to rest the lamp on, or the user is otherwise inconvenienced by carrying some specially provided clamp or attachment for supporting the lamp to direct the light on the object to be illuminated.

Therefore, one of the objects of my invention is to construct a self supporting hand lamp adapted to maintain a beam of light in any direction.

Another and more specific object of my invention is to construct a hand lamp adapted to rest on its side or its base end and provided with a light projector rotatably mounted on a lateral axis extending from the head of the lamp to prevent it from rolling while lying on its side and to provide a means for supporting the projector in any position to which it may be revolved about its axis while the lamp is resting on its side or standing on its end.

The objects of my invention will be more clearly understood from the following description and accompanying drawings, in which

Figs. I to III are sectional views of different modifications of my invention; Figs. IV and V are views on lines IV-IV and V-V in Figs. II and III respectively; Fig. VI is a top end view of the light head; and Figs. VII and VIII are sectional and end views respectively of the swivel head joint in Fig. I.

In Fig. I, a lamp head 1 is mounted on a base or battery casing 2 having a base end 3. The head comprises a stationary tubular elbow 4 coupled to the battery casing by a screw threaded connection 5 and a second tubular elbow 6 pivotally joined to the sta-

tionary elbow 4 by a swivel joint 6a on an axis common to their adjacent ends. The end of the stationary elbow adjacent to the pivoted elbow is indented to form a crescent shaped ledge 7 therein. An inwardly formed flange 8 is provided on this end of the elbow at the inner edge of the ledge. A cup-shaped ring 9 having an inwardly turned flange 10 secured coaxially to the stationary elbow flange 8 by rivets 11 is provided with screw threads 55 on its cylindrical walls 12.

The end of the pivoted elbow 6 adjacent to the stationary elbow 4 is provided with an indented ledge 13 and an inwardly turned flange 14 similar to the ledge and the flange 65 of the stationary elbow 4. A threaded cup-shaped ring 15 similar to the previously described ring is provided with a flange 16 which is secured to the flange 14 by rivets 18.

The form of the swivel joint 6a shown in Figs. I, VII and VIII is particularly suitable for the modification of my lamp shown in Fig. I, but this joint also may be used for the other modifications. The joint comprises two cup-shaped rings 20 which are similar 70 to the rings 9 and 15 and are provided with screw threads along their cylindrical wall 21 to engage the corresponding screw threads 22 along the cylindrical walls of the rings 9 and 15 secured to the elbows. Each of the joint 75 rings 20 is provided with an inwardly turned flange or disc 22 which abut each other and has a circular central opening therein. Flat clamping rings 23 and 24 having a central 80 opening registering with the central openings in the abutting flanges 22 of the joint 85 rings 20 are placed on each side of the flanges. Flexible projections 25 extend laterally from the inner periphery of the clamping rings in opposite directions through the central 90 openings in the joint ring flanges 22 and are bent over the opposite clamping ring towards their outer peripheries. The bend in the projections is so formed as to clamp the flanges 22 of the joint rings 20 between the 95 clamping rings 23 and 24 under the spring tension of the projections 25 and to hold the joint rings in sliding contact with each other with sufficient friction to maintain the pivoted elbow 6 at any point to which it may be 100

turned. In this form of the swivel joint means are provided to limit the number of turns of the pivoted elbow 6 about its axis in either direction to about two revolutions. 5 The means comprises a lug 26 on the outer periphery of the clamping ring 23 cooperating with a stop 27 on one of the joint ring flanges 22 and another lug 28 on the other clamping ring 24 cooperating with a stop 29 10 on the other joint ring flange 22. As shown in Figs. VII and VIII the stop 27 is on the joint ring secured to the pivoted elbow 6 which has been rotated to its extreme clockwise position. To rotate the elbow 6 to its 15 extreme counter-clockwise position from the position shown the lugs and stops cooperate with each other in the following manner. The stop 27 will pass around the outer periphery of the clamping ring 23 until it comes 20 in contact with the edge of the lug 26 facing the clockwise direction. The stop 27 and the lug 26 may then be rotated together until the edge of the clamp projections 25 on this ring facing a counter-clockwise direction 25 comes in contact with the edge of the clamp projections 25 on the other clamping ring 24. The two clamping rings may now be rotated together by the elbow 6 until the edge of the lug 28 facing the counter-clockwise direction 30 comes in contact with the stop 29 on the joint ring 20 fixed to the stationary elbow 4.

A clip 30 is secured to the top of the stationary elbow 4 which may be used to fasten the lamp to a person's vest pocket or other 35 objects while the light may be turned and directed upon the desired object.

In the outer end of the rotatable elbow 6 an incandescent light bulb 31 is mounted in a socket 32 secured to an insulating disc 33 40 by a rivet 34. The insulating disc rests on a ledge 35 in the elbow 6 and is maintained in place by a spring ring 36 in contact with the disc and fitting into a groove in the elbow 6. The end portion of the elbow 6 is threaded 45 to receive cooperating threads on a lens ring 37. A lens 38 and a reflector 39 which fits loosely around the incandescent bulb 31 are mounted as a unit in the lens ring 37 which may be screwed in or out the elbow 6 to focus 50 the light.

The incandescent light 31 is in an electrical circuit between the terminals of the battery 40. A portion of one side of the circuit is formed in the usual manner through 55 the battery casing 2 in contact with the lower terminal of the battery and a switch 41 on the casing which is adapted to control the connection between the casing 2 and a switch contact 42 riveted to an insulating disc 43 secured between a shoulder on the stationary elbow 4 and the top of the battery casing 2. The remaining portion of this 60 side of the circuit comprises a flexible covered wire 44 secured at one end to the switch contact 42 and at the other end to the rivet 34 in

contact with the bulb socket 32. The other side of the incandescent light circuit comprises a center bulb contact 45 secured to the insulating disc 33 by a rivet 46, and a flexible covered wire 47 attached at one end to the rivet 46 and at the other end to a battery terminal contact 48 riveted into the insulating disc 43 and making contact with the upper battery terminal. Sufficient slack is allowed in the wire leads 44 and 47 to permit the elbow 6 to be turned through at least two revolutions or until the elbow is arrested by the swivel joint stops 27 and 29 without taking up all of the slack. 70 75

The modifications of my invention shown in Figs. II and III are similar to the modification shown in Fig. I except for the electrical circuit in the lamp head and also except for the form of the swivel joint, only these dissimilar parts will be described in detail. The parts of my invention in Figs. II and III which correspond to the similar parts in Fig. I will be designated by the same reference numerals as in Fig. I with the addition of 200 and 300 respectively. 80 85 90

The lamps in Figs. II and III are constructed so that the pivoted elbow can be rotated continuously in either direction without injury to the electrical circuit. Therefore, no means is provided in the swivel joint 95 in connection with these modifications to limit the number of turns of the elbow. This joint is the same in both Figures II and III and therefore will be described only in Fig. II. The joint rings 220 in Fig. II are similar to those in Fig. I. Their abutting flanges 222 are adapted to slide on one another and are held in frictional contact between a flat ring 223 and a clamping ring 224 by the spring tension of the bent projections 225 100 extending from the inner periphery of the clamping ring and over the flat ring 223. 105

In Fig. II the incandescent bulb 231 is mounted in a socket 232 secured to and below the insulating disc 233. The disc 233 is held 110 in the elbow 206 in the same manner as in Fig. I. The incandescent bulb 231 is in a circuit between a battery terminal contact 248, in circuit with one terminal of the battery, and a switch contact 242 which may be placed in 115 circuit with the other battery terminal by means of the usual switch. The circuit between the two contacts 248 and 242 comprises a spring contact post 249 carried by an insulating plate 243 mounted in the stationary elbow 204 adjacent to the top of the battery casing 202. The post is secured at one end to the insulating plate by a rivet 250 which forms the contact 248 for the upper battery terminal. 120 125

The upper end of the post 249 is provided with a socket 251 coaxial with the common axis of the adjacent ends of the elbows. A tubular conductor 252 extending along the common axis of the elbows is received at one 120 125 130

end by the socket 251. The other end of the tubular conductor is provided with a flange 253 which is attached to the pivoted elbow 206 and rotates therewith. The conductor 252 is insulated from the elbow 206 by an insulating disc 254 secured by rivets 218 to the inwardly turned flange 214 of the elbow 206. The flange 253 of the conductor 252 is fixed to the disc 254 by rivets 255 passing through the flange, the disc and a bulb contact 256 on the opposite side of the disc from the flange. The other bulb contact 257 is secured to the insulating disc 254 by the beaded end of a conductor rod 258 passing through the center of the tubular conductor 252 and through the insulating disc 254. The opposite end of the rod 258 extends beyond the end of the tubular conductor 252 and passes through an opening in a spring contact post 259 secured to the insulating disc 243 at the top of the battery casing 202. The foot of the post 259 is secured to the disc 243 by the switch contact rivet 242 which passes through the disc. The upper end of the post 259 is bent downwardly in the form of an inverted U. The downwardly bent portion is provided with a socket 260 to receive the end of the conductor rod 258.

In Fig. III the incandescent bulb 331 is mounted in the elbow 306 in the same manner that the bulb in Fig. II is mounted. The bulb is in a circuit comprising a spring post 349 secured to an insulating disc 343 by a rivet 348 which passes through the foot of the post and the disc. The head of the rivet on the opposite side of the disc from the post forms the contact for engaging the center battery terminal. The upper end of the post 349 engages the rotatable surface of a hollow tubular conductor 352 secured to the pivoted elbow 306 at one end and journaled near the other end in an axial hole in an insulating disc 308a secured to the stationary elbow 304 by rivets 311 passing through the inwardly turned flange 308 on the elbow. The tubular conductor 352 is provided with a flange 353 which is secured to the insulating disc 354 by rivets 355. One of the rivets 355 also passes through an L shaped bulb contact 356 and secures it to the disc in contact with the tubular conductor 352. The bulb contact passes through a hole 354a in the insulating disc 354 and is connected with the central terminal of the light filament. The other terminal of the light filament is connected with a spring contact strip 357 secured to the insulating disc 354 by the beaded end of a conductor rod 358 extending through the insulating disc 354. The rod 358 passes through the tubular conductor 352 and is coaxial therewith. An insulating bushing 352a fits within the end of the tubular conductor 352 opposite the insulating disc 354. The rod 358 passes through a bore 352b in the bushing 352a which provides a support for that end of the

rod. The projecting end of the rod 358 makes sliding contact with a spring post 359 secured to the insulating disc 343 by the switch contact rivet 342.

It will be seen from the foregoing construction that I have provided a convenient means for placing a lamp at rest under various conditions while the light is projected upon the desired object. In addition to laying the lamp on its side or standing it on its base end, it may be suspended from any convenient object by the spring clip on the light head.

The device with its modifications shown and described herein, are illustrative of my invention. Various changes may be made in the details of the structure without departing from the scope of my invention defined in the appended claims.

I claim:

1. A hand lamp, comprising a tubular head and a base, said head having a member fixed to the base, a light projector swiveled on said member, a swivel joint between the fixed head member and said projector, said joint comprising two rings having juxtaposed inwardly flanged portions and a cylindrical portion, the cylindrical portion of one ring being joined to the tubular portion of the fixed head member, and the cylindrical portion of the other ring being joined to the projector, a clamping ring in contact with the flange of one joint ring, projections on said clamping ring extending through a circular central aperture in each of the flanges and bent along the walls of the flanges to hold them in frictional contact.

2. A battery hand lamp, comprising the combination of a battery casing and a head, said head comprising an L-shaped tubular member having the end of one arm of the L attached to said casing, a plate secured in said end, insulated battery terminal contacts anchored in said plate and extending therethrough; a second member rotatably attached to the other arm of the L, an incandescent light carried in the second member, a plate secured in said second member between the light and the first member, insulated contacts anchored in said second plate and extending therethrough to the light contacts, and insulated conductors extending between the contacts in the first and second plates.

3. A swivel joint comprising two abutting discs each having a central opening therein, a clamping ring having projections thereon extending through said openings and bent outwardly towards the outer periphery of said discs to hold the discs in sliding contact with each other between the ring and the projections, and means on said clamping ring and said discs to limit the number of turns one disc may make relative to the other.

4. A swivel joint comprising two abutting discs each having a central opening therein,

a clamping ring on each side of said discs, projections on said clamping rings extending in opposite directions through said openings and bent outwardly towards the outer periphery of the flanges to hold the discs in sliding contact with each other between the clamping rings and the projections, and means for limiting the number of turns of said discs relatively to each other comprising a lug on each clamping ring and a stop on each disc projecting in the arc of travel of the lug on the adjacent ring.

5. A hand lamp comprising a tubular head and a base, said head having a member fixed 15 to the base, a light projector supporting member swiveled on said fixed member, a swivel joint between the fixed head member and said projector supporting member, said joint comprising two juxtaposed discs having 20 a central opening in each, one of said discs being attached to the fixed head member and the other disc being attached to the swiveled head member, a clamping ring in contact with one of said discs, and projections 25 on said clamping ring, said projections extending through the central opening in each of said discs and bent towards the outer periphery of said discs to hold the discs in frictional sliding contact with each other.

30 6. A hand lamp comprising a tubular head and a base, said head having a member fixed to the base, a light projector supporting member swiveled on said fixed member, a swivel joint between the fixed head member 35 and said projector supporting member, said joint comprising two juxtaposed discs having a central opening in each, one of said discs being attached to the fixed head member and the other disc being attached to the swiveled 40 head member, a clamping ring on each side of said disc, projections on said clamping rings, said projections extending through the central opening in each of said discs and bent towards the outer periphery of said discs to 45 hold the discs in frictional sliding contact with each other, and projections on said discs cooperating with projections on said clamping rings to limit the swivel movement of said swivel member.

50 In testimony whereof, I affix my signature.
HOMER W. JONES.
